ABSTRACT

A dioramic running toy including a running member and a dioramic panel removably attached to the running member so as to enable the dioramic panel to run with the running member. The present invention further relates to a dioramic running toy assembly including a plurality of dioramic running toys capable of running in combination.

FIG. 8

DIORAMATIC RUNNING TOY

SUMMARY OF THE INVENTION

It is an object of the present invention to provide a dioramic running toy including a running member and a dioramic panel attached to said running member so as to run said dioramic panel with the running member, capable of assembling various mode of dioramic panels with various mode of running members optionally, and further capable of connecting a plurality of dioramic running toys in combination. The present invention seeks to offer such a dioramic running toy to provide a variable and enjoyable toy with reality for children.

Another object of the present invention is to provide a dioramic running toy having a simple construction economically, and easy to manufacture.

To accomplish the aforementioned objects, the present invention provides a dioramic running toy comprising a running member including a housing and a wheel assembly rotatably mounted to said housing, a dioramic panel having a top surface and bottom surface and provided with through holes perforated from said top surface to said bottom surface for receiving said wheel assembly therein, and connecting means for removably attaching said housing to said dioramic panel so as to enable said dioramic panel to run with said running member.

In accordance with another aspect of the invention, there is provided a dioramic running toy assembly comprising at least a pair of dioramic running toys and connecting means for removably connecting each said dioramic running toy so as to make a dioramic running toy assembly run in combination, each said dioramic running toy including a running member having a housing, a wheel assembly rotatably attached to said housing and a self-contained motor assembly mounted on said housing to drive said wheel assembly, a dioramic panel having through holes for receiving said wheel assembly therein, and attach means for removably attaching said housing to said dioramic panel so as to enable said dioramic panel to run with said running member.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings.

BRIEF DESCRIPTION OF THE DRAWINGS

FIG. 1 is a top perspective view of a dioramic running toy;

FIG. 2 is a bottom perspective view;

FIG. 3 is an exploded perspective view of another embodiment of the present invention;

FIG. 4 is a front elevational view of the embodiment of FIG. 3;

FIG. 5 is a top perspective view of a dioramic running toy assembly of still another embodiment of the present invention;

FIG. 6 is a bottom perspective view of the embodiment of FIG. 5;

FIG. 7 is a partially sectional side view of the embodiment of FIG. 5; and

FIG. 8 is an exploded perspective view of the embodiment of FIG. 5.

DETAILED DESCRIPTION OF THE PREFERRED EMBODIMENTS

The following description is provided to enable any person skilled in the toy industry to make and use the present invention and sets forth the best modes contemplated by the inventor for carrying out his invention.

10 Various modifications, however, will remain readily apparent to those skilled in the art, since the generic principles of the present invention have been defined herein specifically to provide a novel dioramic running toy.

15 Referring now in detail to the drawings, FIG. 1 and FIG. 2 disclose an embodiment of the present invention. FIG. 1 is a top perspective view of a dioramic running toy comprising a running member 2 and a dioramic panel 3. The running member 2 includes a housing 4 and

20 a wheel assembly 2a rotatably mounted on said housing 4 and driven by a prime mover, such as in the running toy disclosed in the U.S. Pat. No. 4,329,810, while the dioramic panel 3 is removably attached to the housing 4 so as to enable the dioramic panel 3 to run with the running member 2.

25 The running member 2 having a prime mover (not shown) accommodated therein, such as a well-known pull back type spring powered prime mover, is capable of running by the rotation of the wheel assembly 2a, the rear wheel assembly for example, driven by the prime mover.

30 There are provided three L-shaped prongs 2b for connecting and securing the dioramic panel 3 on the bottom surface of the housing 4 of the running member 2.

35 The dioramic panel 3 is formed as a rectangular plate-like configuration, and has four holes 3a for rotatably receiving the wheel assembly 2a therein, and three receiving holes 3b for receiving and connecting the prongs 2b therein. Each of the through holes 3a and the receiving holes 3b is arranged to locate around the center of the dioramic panel 3.

40 Furthermore, the dioramic panel 3 can be provided with a decoration on its surface which, for example, simulates the scene of war corresponding to the configuration of the running member 2 simulating a military jeep as shown in FIG. 1. For that purpose, simulating members S may be adhered to the surface of the dioramic panel 3.

45 The dioramic running toy 1 is assembled by fitting the prongs 2b into the receiving holes 3b, while rotatably inserting the wheel assembly 2a into the through holes 3a, whereby connecting the dioramic panel 3 with the running member 2.

50 Thus assembled, dioramic running toy 1 is capable of running in response to the motive power of the running member 2, for example, by pushing rearward the running member on a support surface to provide a counterclockwise rotation to said wheel assembly 2a to wind a spring motor assembly if a pull-back type spring powered prime mover is mounted on the running member 2.

55 FIG. 3 and FIG. 4 disclose another embodiment of the present invention, which is provided with a different construction of a dioramic panel from aforementioned embodiment.

60 Namely, a dioramic panel 13 is provided with a main plate 13a and a rear panel 13e vertically attached to the rear end of the main plate 13d, thereby forming

an L-shaped configuration. On the front surface of the rear panel 13e, there is provided a background, for example, simulating a sight corresponding with the running member 12 simulating a toy sports car.

In the same way as aforementioned embodiment, a dioramic running toy 11 is composed so as to enable the dioramic panel 13 to run with the running member 12 by the rotation of a wheel assembly 12a rotatably inserted into through holes 13a while prongs 12b, 12c are inserted into receiving holes 13b, 13c for connecting the dioramic panel 13 with the running member 12.

This embodiment provides more enjoyable dioramic running toy as the dioramic panel 13 is tridimensional.

FIG. 5-FIG. 8 disclose still another embodiment of the present invention. Numeral 100 indicates a dioramic running toy assembly comprising dioramic running toys 200 and 300 each including a running member and a dioramic panel, and a connecting member 400 for connecting the dioramic running toys 200 and 300 each other.

The dioramic running toys 200 and 300 comprise respectively a running member 25 which simulates a military truck and a running member 27 which simulates a tank with a caterpillar-like simulating member 174 attached thereto, and dioramic panels 26 and 28 provided with decoration on their surfaces are attached to the running members 25 and 27, respectively, so as to enable the dioramic panels 26 and 28 to run with the running members 25 and 27.

Each running member 25, 27 mounted with a prime mover, such as a pull back type spring powered prime mover in the same manner as aforementioned embodiment, is capable of running by the rotation of each rear driving wheel assembly 52, 72, driven by the prime mover, while being accompanied by the rotation of each front idling wheel assembly 54, 73.

Each rear wheel assembly 52, 72 rotatably attached to the both sides of the rear end of the housing 51, 71 of the running member 25, 27, has a larger diameter than each front wheel assembly 53, 73, rotatably attached to the both sides of the front end of the housing 51, 71, of the running member 25, 27.

On the bottom surfaces of each housing 51, 71, of the running member 25, 27, a pair of female type receptacles 54, 74, is provided about the both sides of the bottom surface and at around the center in the longitudinal direction as shown in FIG. 8.

Further, the dioramic panels 26, 28 are formed as a disk-like configuration, and each dioramic panel 26, 28 has two pairs of through holes about the center thereof for rotatably receiving the front and rear wheel assemblies 52, 53, 72, 73; i.e. through holes 62, 82 for receiving rear wheel assembly 52, 72, and through holes 63, 83 for receiving front wheel assembly 53, 73, respectively.

On the surfaces of each dioramic panel 26, 28, a pair of male type prongs 64, 84 are further provided between the through holes 62 and 63 and the through holes 82 and 83, respectively, so that the prongs 64, 84 are fitted into the receptacles 54, 74 provided on the bottom of the running members 25, 27.

The dioramic panels 26, 28 can be provided with decorations on their surfaces such as a background simulating the scene of war corresponding to the military type running members 25, 27, for example.

The dioramic running toys 200, 300, are assembled from the running members 25, 27, and the dioramic

panels 26, 28, by fitting the male type prongs 64, 84 into the receptacles 54, 74, while rotatably inserting the front and rear wheel assemblies 52, 54, 72, 73 into the through holes 62, 63, 82, 83, respectively.

5 The connecting member 400 is provided with two projections 42, 43, stuck up apart on its surface to connect the dioramic panels 26 and 28 by inserting the projections 42, 43 respectively into connecting holes 65, 85 perforated about the edge of the dioramic panels 26, 28. The projections 42, 43 are arranged to adjust or compensate the difference of height between dioramic panels 26, 28.

15 Each running members 25, 27, of the dioramic running toys 200, 300, inclines forward when it is placed on a flat support surface because each rear wheel assembly 52, 72, which drives the running member 25, 27, is provided with a larger diameter than the front wheel assembly 53, 73, which idles corresponding to the rotation of the rear wheel assembly 52, 72. Accordingly, each 20 dioramic panel 26, 28 attached to the running member 25, 27, also inclines forward corresponding to the incline of the running member 25, 27. Such conditions cause the difference of height h between the rear end of the dioramic panel 26 and the front end of the dioramic panel 28, when the dioramic running toy 200, 300, is put on a support surface in a single file. Therefore, the connecting member 400 is arranged in tiers to adjust the difference of height between the rear end of the dioramic panel 26 and the front end of the dioramic panel 28.

25 That is, the connecting member 400 comprises a disk-like basic plate 41, a tiered-columnar connecting projection 42 arranged on the front portion of the upper surface of the basic plate 41, and a columnar connecting projection 43 arranged on the rear portion of the upper surface of the basic plate 41.

30 The connecting projection 42 is arranged in tiers to correspond with the difference of height h, including a basing portion 42a provided on the basic plate 41 and an inserting portion 42b provided on the center of the basing portion 42a. The basing portion 42a having a larger diameter than that of the inserting portion 42b, has the same height as the difference of height h.

35 Further, about the edge of each dioramic panel 26, 28, circular connecting holes 65, 85 are perforated for receiving and connecting the connecting projections 42, 43, respectively.

The dioramic running toys 200 and 300 are connected through the connecting member 400 by inserting the connecting projections 42, 43 of the connecting member 400 into the connecting holes 42, 43, respectively.

40 Thus provided dioramic running toy assembly 100 is capable of running in response to the motive power of the running members 200, 300, for example, by pushing rearward at least one of the running members 200, 300 on a support surface to wind a spring motor assembly if well-known pull back type spring powered prime movers are mounted on the running members 200, 300.

45 In addition to the embodiments described above, the dioramic running toy assembly of the present invention can be also assembled to comprise more than two dioramic running toys connected each other.

50 As can be readily appreciated, a dioramic running toy of the present invention comprising a running member and a dioramic panel removably attached to said running member so as to run said dioramic panel with said running member, is capable of assembling various

mode of dioramic panel with various mode of running member optionally, and further capable of connecting a plurality of dioramic running toys for providing such a dioramic running toy which is changeful, variable, with reality, and more enjoyable for children.

Since the connecting member simply has two connecting projections arranged in tiers, a plurality of dioramic running toys can be connected easily and firmly, adjusting the difference of height between dioramic panels in connecting the dioramic running 10 toys.

Additionally, the connecting member has such simple construction that it is easy and economic to manufacture.

I claim:

1. A dioramic running toy comprising:
a running member including a housing and a wheel assembly rotatably mounted to said housing;
a dioramic panel having a top surface and a bottom surface and provided with through holes perforated from said top surface to said bottom surface for receiving said wheel assembly therein, said top surface comprising means portraying a scene which provides a setting for said running member; and
25 connecting means for removably attaching said housing to said dioramic panel with said wheel assembly received in said holes so as to enable said dioramic panel to run with said running member.
2. A dioramic self-propelled running toy comprising:
30 a running member including a housing and a wheel assembly rotatably mounted to said housing;

15

25

30

a dioramic panel having a top surface and a bottom surface and provided with through holes perforated from said top surface to said bottom surface for receiving said wheel assembly therein, said top surface comprising means portraying a scene which provides a setting for said running member; connecting means for removably connecting said running member to said dioramic panel with said wheel assembly received in said holes and including a set of male type connectors provided on one of the dioramic panel and said housing and a set of female type receptacles on the other; and a self-contained motor assembly mounted on said housing to drive said wheel assembly.

3. A dioramic running toy assembly comprising; at least a pair of dioramic running toys; and connecting means for removably interconnecting said dioramic running toys so as to make a dioramic running toy assembly run in combination; each said dioramic running toy including a running member having a housing, a wheel assembly rotatably attached to said housing and a self-contained motor assembly mounted on said housing to drive said wheel assembly, a dioramic panel having through holes for receiving said wheel assembly therein, and attaching means for removably attaching said housing to said dioramic panel with said wheel assembly received in said holes so as to enable said dioramic panel to run with said running member, said panel comprising means portraying a scene which provides a setting for said running member.
